UNITED STATES PATENT OFFICE.

JOSEPH SOBEL, OF NEW YORK, N. Y.

VENTILATOR.

Application filed August 16, 1926. Serial No. 129,519.

This invention relates to ventilators and has particular reference to a ventilator which is disposed above the roof of a building and is provided with a plurality of 5 openings with closures therefor, the invention particularly residing in the mechanism for simultaneously closing and opening said closures.

One of the principal objects and advantages of the present invention is to provide a ventilator of the character set forth, which in addition to giving a maximum opening for ventilation and minimizing the danger of freezing, facilitates both the operations 15 of closing and opening the closure elements while reducing the power required to effect the operations.

Other objects reside in the simplicity of construction, the economy with which the 20 same may be produced and erected, and the general efficiency of operation.

With the above recited and other objects in view, reference is had to the following specification and accompanying drawings in 25 which there is exhibited one example or embodiment of the invention which is in no way intended as a limitation upon the scope of the appended claims as it is to be clearly understood that variations and modifications 30 which properly fall within the scope of said claims may be resorted to when found expedient.

In the drawings—

Figure 1 is a diagrammatic sectional plan 35 view illustrating the device in full and broken lines, respectively in its closed and open conditions;

Fig. 2 is an end view partly in section, with the closures in open condition;

Fig. 3 is a fragmentary enlarged sectional view with the closures in closed condition;

Fig. 4 is a fragmentary enlarged horizontal sectional view illustrating the device respectively in full and broken lines, in its 45 closed and open condition.

The ventilator constituting the present invention may form part of a skylight, if desired, but in any event a rectangular super-structure 10 extending above the roof 50 of a building will be employed, and the same will be provided with a plurality of apertures 11, each of which has a closure 12 hinged along one vertical edge at 13 to swing horizontally outward from a closed 55 to an open position. The apertures 11 preferably will be defined by a framework 14

between which hollow mullions 15 are disposed. Each closure on its inner face has hingedly connected thereto at 16, an arm 17, and the arms 17 of the closures of each side of the super-structure 10, are pivotally connected at 18 to a link bar 19. Within each mullion 15, a sheave 20 is mounted on a horizontal shaft 21 and cables or other flexible elements 22 are trained over the 60 sheaves 20 and are provided with weights 23 at one end to permit of vertical movement of the weights within the mullions. The opposite ends of the cables or flexible elements 22 extend through openings 24 on 65 the inner walls of the mullions and are connected at 25 to the link bars 19. Under this arrangement it is obvious that all the closures of each side of the super-structure 70 are connected for simultaneous movement, while the weights 23 being sufficiently heavy, serve to normally exert an outward pull on the link bar to normally swing the closures to an open position.

In order to provide means for manually 80 moving the link bars 19 simultaneously inward to close the closure elements, the link bars have each connected thereto at one or more points, preferably at two points, the extremities 26 of cables 27, which cables 28 are trained over sheaves or pulleys 28 carried by blocks 29 swiveled to a hanger 30 which is suspended from the center of the upper portion of the superstructure 10, the opposite ends of the cables or flexible 85 elements 27 being connected to a common depending operating cable or rope 31.

Under this construction and arrangement 90 it is obvious that a pull exerted on the operating cable 31 sufficient to overcome the 95 combined weight of the weight elements 23, will effect the closing of the closure elements. The operating cable or rope 31 may be engaged with a cleat or otherwise secured to hold the closures in closed condition. 100 When it is desired to open the closures, the operating cable 31 is released to allow the weights to function to swing the closures to an open condition.

It will be seen from the foregoing that 105 in addition to obtaining a full opening of the ventilator and minimizing the chances of the closures freezing and sticking in their closed condition, the operation of opening or closing the same is greatly facilitated. 110 It is, of course, to be understood that the super-structure 10 will be provided with a

roof 32, which roof may be in the nature of a transparent or translucent material to permit of the passage of light therethrough where the device is used as a sky-light.

5. What is claimed is:

1. A ventilator including a plurality of walls, each having a plurality of apertures, a horizontally swingable closure for each aperture, an arm hinged to the inner side 10 of each closure, a link connecting the arms of the closures of each wall, means connected with each link for normally shifting the same in a direction to open the closures, and a common means connected with the 15 links for manually moving the same in a direction to close the closures.

2. A ventilator including a plurality of walls, each having a plurality of apertures, a horizontally swingable closure for each 20 aperture, an arm hinged to the inner side of each closure, a link connecting the arms of the closures of each wall, weights for each closure connected to the links for normally moving the links to a position for 25 opening the closures, and a common means of connection between the links for manually moving the same in a direction for closing the closures against the action of the weights.

3. A ventilator including a rectangular super-structure closed at the upper end and open at the lower end, said super-structure having a plurality of apertures in each of 35 its walls and provided with hollow mullions between the apertures, a horizontally swingable closure for each aperture, an arm hinged to the inner side of each aperture and extending inwardly, a link bar pivotally connected to the inner ends of the arms 40 of the closures of each wall, a sheave in each

mullion, a cable trained around each sheave, having a weight attached to one end of the cable and vertically movable in the mullion and said cable being connected at its opposite end to the link bar, whereby simultaneous outward swinging movement of the closures to an open position is effected, and means for manually moving the link bars simultaneously inward for closing all of the closures against the action of the 45 weights.

4. A ventilator including a rectangular super-structure closed at the upper end and open at the lower end, said super-structure having a plurality of apertures in each of 50 its walls and provided with hollow mullions between the apertures, a horizontally swingable closure for each aperture, an arm hinged to the inner side of each aperture and extending inwardly, a link bar pivotally connected to the inner ends of the arms of the closures of each wall, a sheave in each 55 mullion, a cable trained around each sheave, having a weight attached to one end of the cable and vertically movable in the mullion, and said cable being connected at its opposite end to the link bar whereby simultaneous outward swing movement of the closures to an open position is effected, and means for 60 manually moving the link bars simultaneously inward for closing all of the closures against the action of the weights.

5. A ventilator including a rectangular super-structure closed at the upper end and open at the lower end, said super-structure having a plurality of apertures in each of 65 its walls and provided with hollow mullions between the apertures, a horizontally swingable closure for each aperture, an arm hinged to the inner side of each aperture and extending inwardly, a link bar pivotally connected to the inner ends of the arms of the closures of each wall, a sheave in each 70 mullion, a cable trained around each sheave, having a weight attached to one end of the cable and vertically movable in the mullion, and said cable being connected at its opposite end to the link bar whereby simultaneous outward swing movement of the closures to an open position is effected, and means for manually moving the link bars simultaneously inward for closing all of the closures against the action of the weights, said latter means comprising cables attached at one end respectively to the link bars and joined together at the other ends, sheaves over which said cables are trained, and a common manipulating element connected with said cables.

JOSEPH SOBEL.
